E. HYMAN

STAIR COVERING

Filed Oct. 6, 1923

INVENTOR

Elias Hyman.

BY

Solomon Polachek
ATTORNEY

UNITED STATES PATENT OFFICE.

ELIAS HYMAN, OF BROOKLYN, NEW YORK.

STAIR COVERING.

Application filed October 6, 1923. Serial No. 666,893.

To all whom it may concern:

Be it known that I, ELIAS HYMAN, a citizen of the United States, residing at Brooklyn, in the county of Kings and State 5 of New York, have invented certain new and useful Improvements in Stair Coverings, of which the following is a specification.

This invention relates generally to stair coverings, having more particular reference 10 to a stair covering made up of separate elements adapted for individual application to the respective steps.

The invention has for an object the provision of a novel and simple stair covering 15 which can be readily applied to the stairs to have the appearance of a continuously extending cover.

For further comprehension of the invention, and of the objects and advantages 20 thereof, reference will be had to the following description and accompanying drawing, and to the appended claims in which the various novel features of the invention are more particularly set forth.

25 Fig. 1 of the drawings is a perspective view showing my improved covering in place on a stairway.

Fig. 2 is a face view of one of the covering sections, showing the latter unbent.

30 Fig. 3 is a transverse sectional view thereof taken on the line 3—3 of Fig. 2.

Fig. 4 is a similar view of Fig. 2 but showing a modification.

35 Fig. 5 is a transverse sectional view taken along the line of 5—5 of Fig. 4 but showing the cover with one side upturned in the position assumed when in place on a stairway.

In constructing my improved stair covering I provide individual elements each 40 adapted to extend across a step and up the face of the next higher step to a point adjacent the top thereof, and also to project slightly downward at the front of the step to register with the next cover element. Each 45 element comprises briefly a facing member, preferably of carpet, a stiffening member, and a base member to which the facing member is attached, the stiffening member preferably possessing sufficient rigidity to hold 50 the facing member properly extended over the step, while being sufficiently flexible to permit of bending to assume the position on the step above noted.

In the present instance I attach to the 55 underside of the facing member, indicated at 10 in the drawing, the sheet 11 of felt

paper or other like material which forms a base member, these parts 10 and 11 being stitched first together by a longitudinal line of stitching 12 located at the point where 60 the cover is to be bent to extend up the face of the adjacent step. These parts 10, 11 are of substantially equal area and are of a sufficient width to extend over the step in the manner above set forth. A second sheet 14, 65 of like material to the sheet 11, is then placed under the sheet 11 and the three parts 10, 11 and 14 are then stitched together along three sides as indicated at 15, leaving them unattached along the fourth side for the insertion of the stiffening member, and also of a filling material 18 between the facing material 10 and the base member 11 and at one side of the line of stitching to form a pad or cushion on the step. This stiffening member 70 is here in the form of a comparatively thin sheet 20 of copper and is inserted between the two felt paper sheets 11 and 14, being of slightly less area than these sheets so as to be confined within the stitched edges 75 of the latter. The parts 10, 11 and 14 are then stitched together along the fourth side, completing the cover element except for the necessary bending which is done at the time 80 the cover is applied to the step. The cover 85 may be secured in place by screws, nails or other suitable fastening elements.

In Figs. 4 and 5 I have shown a slightly modified construction which may be manufactured at less cost. This comprises the 90 facing material 10, while a backing sheet 14' of less width is stitched thereto along three sides, a stiffening plate 20' of copper or of another cheaper metal, and a filling 18' being inserted between the two members 10 and 95 14'. The member 10 projects at one side beyond the backing 14', which latter is of a width corresponding to the front to rear dimension of the step, and may have a wire 22 attached to and extending around the 100 edges thereof. This wire serves to hold the upwardly projecting portion of member 10 properly stretched, this upwardly projecting portion being less liable to distortion than that extending over the top face of the 105 step.

Having thus described my invention what I claim as new and desire to protect by Letters Patent of the United States is as follows:

110 1. A stair covering element comprising a facing member, a pair of sheet members at-

tached at their edge thereto to form a pocket between said sheet members and a stiffening member in the said pocket, one of said sheet members being attached to the facing member along a line located between opposite edges of the covering element.

2. A stair covering element comprising a facing member, a pair of sheet members attached at their edge thereto to form a pocket between said sheet members and a stiffening

member in the said pocket, one of said sheet members being attached to the facing member along a line located between opposite edges of the covering element, and a padding material inserted between said facing member and last mentioned sheet members at one side of said line.

In testimony whereof I have affixed my signature.

ELIAS HYMAN.
